US00D517058S

(12) United States Design Patent (10) Patent No.: US D517,058 S
(45) Date of Patent: * Mar. 14, 2006

(54) COMBINED DISC RECORDER AND AMPLIFIER

(75) Inventor: Toshiyuki Hisatsune, Tokyo (JP)

(73) Assignee: Sony Corporation, Tokyo (JP)

() Term: 14 Years

(21) Appl. No.: 29/198,928

(22) Filed: Feb. 9, 2004

(51) LOC (8) Cl. 14-01

(52) U.S. Cl. D14/257

(58) Field of Classification Search D14/445, D14/260.1, 258, 257, 224, 217, 198, 197, D14/196, 195, 194, 193, 192, 188, 168, 167, D14/156, 136, 191, 157; D12/415, 420; 455/344, 455/350, 347; 248/27.3, 27.1, 558

(57) CLAIM

The ornamental design for a combined disc recorder and amplifier, as shown and described.

DESCRIPTION

FIG. 1 is a perspective view of a disc recorder showing my new design;

FIG. 2 is a front elevational view thereof;

FIG. 3 is an enlarged left side elevational view thereof;

FIG. 4 is an enlarged right side elevational view thereof;

FIG. 5 is a top plan view thereof; and,

FIG. 6 is a bottom plan view thereof.

Portions in broken lines are for illustrative purpose only and form no part of claimed design.
